UNITED STATES PATENT OFFICE.

SADIE M. BATES, OF NEWARK, NEW JERSEY, ASSIGNOR, BY DIRECT AND MESNE ASSIGNMENTS, TO GEORGE F. HALL, OF SAME PLACE, AND LEWIS M. THOMPSON, OF MONTCLAIR, NEW JERSEY.

LUGGAGE-CARRIER FOR VELOCIPEDES.

SPECIFICATION forming part of Letters Patent No. 499,903, dated June 20, 1893.

Application filed December 2, 1892. Serial No. 453,821. (No model.)

To all whom it may concern:

Be it known that I, SADIE M. BATES, residing at Newark, in the county of Essex and State of New Jersey, have invented certain new and useful Improvements in Luggage-Carriers for Velocipedes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to improvements in luggage carriers for velocipedes or other like vehicles, adapted to be attached to any suitable part of the velocipede.

The invention has for its main purpose to provide a strong and cheaply constructed carrier, which is of such a construction as to be capable of a quick and convenient application and removal.

The invention therefore consists essentially of a support adapted to be tightly attached or secured to the frame of the vehicle, and a yoke or carrier frame, adapted to be turned into holding engagement with said support on the vehicle frame, and means for automatically locking the parts together.

The invention further consists of certain other arrangements and combinations of parts, such as will be hereinafter more fully described, and finally embodied in the clauses of the claim.

In the drawings, Figure 1 is a plan view of my improved form of luggage carrier, provided with an adjustable package holding frame, said view illustrating two positions of said holding frame. Fig. 2 is a vertical section, taken on line x in Fig. 1, looking in the direction of arrow x' , clearly illustrating the arrangement of one form of spring-actuated pawl in engagement with the teeth of a ratchet wheel, said pawl being in the form of a lever.

Fig. 3 is a similar view, illustrating the position of the pawl when forced out of engagement with the ratchet wheel. Fig. 4 is a vertical section taken on line y in Fig. 1, clearly showing the arrangement of a support secured to the steering head of a velocipede,

and the yoke or carrier frame in its locked or holding engagement with the forked end of said support. Fig. 5 is a front edge view of parts of said support and the carrier frame, clearly illustrating a plate provided with a spring-tongue projecting into a recess in the carrier frame, to prevent its turning on the upper forked end of the support, when turned into holding engagement therewith. Fig. 6 is a like view of these parts, illustrating the position of the spring-tongue when securing the yoke or carrier frame on or detaching it from the support. Fig. 7 is a perspective view of said spring-plate formed with the upwardly extending tongue. Fig. 8 is a perspective view of the pawl, and Fig. 9 is a like view of the spring.

Similar letters of reference are employed in each of the above described views, to indicate corresponding parts.

In said drawings, a is the steering head of a velocipede, and b and c are the two members of a clamp adapted to be secured by means of bolts or screws b' to the steering head of the vehicle, as clearly shown in Fig. 4. From said clamp c , extends a suitable arm c' , which is provided at its free end with an enlarged portion c^2 , preferably plate-shaped, having a centrally arranged post c^3 thereon, from which extend the oppositely placed lugs or holding jaws c^4 and c^5 respectively. Said plate c^2 is provided in its front edge with a recessed or cut-away portion c^6 , and secured to said arm c' and directly below said plate c^2 , by means of screws or rivets d' is a spring plate d having a holding tooth or tongue d^2 , which, owing to the spring action of said plate d , normally extends into and projects above said recessed or cut-away portion c^6 in said plate c^2 , as will be seen more especially from Figs. 5 and 6. The forward end d^3 of said plate d , directly in front of said tongue d^2 serves as a finger-piece, to be used as will be described hereinafter.

As will be seen from Figs. 1 and 4, e represents the yoke or carrier frame, which is provided with a centrally arranged slot or opening e' . When it is desired to secure said yoke or carrier frame to the arm c' of the support, the post c^3 and its jaws c^4 and c^5 are inserted

in the opening or slot e' and by a quarter turn said jaws c^4 and c^5 are brought around to stand in the positions illustrated in Fig. 1, the under sides of said jaws firmly binding 5 against the upper surface of the yoke, as will be seen from said Fig. 4. At the same time, the tongue d^2 on said spring plate d passes up into a recessed or cut-away portion e^2 in the yoke or carrier frame e , thereby avoiding 10 any danger of said frame becoming displaced from the support on the steering head a . Said spring-plate d also causes the jaws c^4 and c^5 to firmly bind against the upper surface of the yoke, thereby preventing any objection- 15 able rattling. When it is desired to separate the yoke or carrier frame from its support c' , a pressure on the finger piece d^3 causes the tongue d^2 on the spring plate d to be forced beneath the cut-away portion e^2 , and by means 20 of a quarter turn the parts can be separated and the carrier frame detached from the support c' , as will be clearly understood from an inspection of Figs. 1, 4 and 6. When said yoke or carrier frame has been seated by 25 means of the mechanism just described, on the support attached to the steering head of the vehicle, it extends along the handle bars in such a position in which it can not interfere with the operation of the machine. 30 As will be noticed from the several views of the drawings, said yoke or carrier frame e is provided at its opposite ends with two outwardly extending arms e^3 and e^4 , which may be provided with eyes e^5 on their sides, and 35 in which can be adjustably arranged a sliding frame f , whereby the luggage carrier can be made larger or smaller to carry a large or small package. To said frame f are secured the ends of suitable straps g . Each arm e^3 and e^4 40 is provided at its free end with a loop e^6 through which the ends of said straps are passed and are wound around small pins or axles h adapted to rotate between the downwardly extending flanges or ears e^7 on said arms e^3 and e^4 . 45 Each pin is provided with a finger piece h' for turning the pin and on the opposite end of each pin, projecting toward the inner portion of the luggage carrier, I have arranged a small ratchet wheel i . To each of the inner 50 ears e^7 are also pivoted, the pawls k , each of which is preferably formed with the curved edge k' having the two sharp corners or edges k^2 and k^3 , and which are provided with the suitable curved handle portions k^4 . Within 55 a perforated lug e^8 is secured the end of a spring j , formed with a coil j' which is placed over a suitable post or finger e^9 extending out from the side of each arm e^3 and e^4 . The free end j^3 of each spring j passes over the edge k^2 60 of said pawl and thereby forces the sharp edge k^3 of the pawl into holding engagement with a tooth on the ratchet wheels, as will be seen from Figs. 2 and 4, and thereby securing the straps g in their tightened positions on a bundle or package to be supported on the carrier frame, as will be understood. In order to unwind the straps, the pawls are forced

forward by a pressure on the handle portions k^4 , whereby both of the said sharp portions or edges k^2 and k^3 rest against the spring j , causing the latter to be held in the notched portion k^5 , see Fig. 8, of the edge k^3 , and by means of the downward pressure of the spring, retaining the pawls in their inoperative positions, as illustrated in Fig. 3. When in these 70 positions, the straps can be unwound, and when the rider wishes to tighten them around a package, the pawls are operated and the edges k^3 are again thrown into sliding engagement with the ratchet wheels, and the straps 80 are reeled upon their pins h by turning the finger pieces h' .

Of course, it will be evident, that any other suitable form of spring may be used, and it can be secured to the carrier frame in any 85 convenient manner, and the ends of the straps can be attached directly to the yoke e , in which case the sliding frame f can be dispensed with. I prefer to use this frame however, for the carrier frame proper can there- 90 by be readily adjusted to different sized packages, and when not in use, in order that it may occupy as little space as possible, said frame f can be pushed in, and when the carrier frame is removed from the support c' , it 95 can be readily carried in the pocket.

Having thus described my invention, what I claim is—

1. A luggage carrier for velocipedes, consisting of a clamp having a supporting arm 100 thereon, and a yoke or carrier frame provided with a centrally arranged slot, and oppositely extending lugs or jaws on said supporting arm adapted to be passed through said slot in the yoke or carrier frame, and turned at 105 right angles across said slot, whereby said frame can be turned into holding engagement with said supporting arm, and a spring to prevent the turning of said yoke on said supporting arm, after the parts have been turned 110 into holding engagement, substantially as and for the purposes set forth.

2. A luggage carrier for velocipedes, consisting of a clamp, having a supporting arm thereon, and a yoke provided with a slot or opening e' , a post on said supporting arm provided with oppositely extending lugs or jaws c^4 and c^5 , adapted to be passed through said slot or opening e' , whereby said frame can be turned into holding engagement, with said lugs or jaws on the post on said supporting arm, outwardly extending arms on said yoke provided with straps, perforated lugs e^5 on said arms, and a frame f adapted to slide in said perforated lugs, substantially as and for 125 the purposes set forth.

3. A luggage carrier for velocipedes, consisting of a clamp, having a supporting arm thereon, and a yoke provided with a slot or opening e' , and a recess e^2 , a post on said sup- 130 porting arm provided with oppositely ex- tending lugs or jaws c^4 and c^5 , adapted to be passed through said slot or opening e' , where- by said yoke can be turned into holding en-

gagement with said lugs or jaws, a plate-like portion c^2 on said supporting arm, provided with a recess c^3 , and a spring plate d secured to said supporting arm, provided with a tongue 5 normally projecting into said recess c^3 and adapted to be forced into holding engagement with said recess c^3 in said yoke, substantially as and for the purposes set forth.

4. A luggage carrier for velocipedes, consisting of a clamp, having a supporting arm thereon, and a yoke on said arm, having outwardly extending arms provided with straps, and a frame f and means on said outwardly extending arms in which said frame f is adjustably arranged in relation to said arms, substantially as and for the purposes set forth.

5. A luggage carrier for velocipedes, consisting of a clamp, having a supporting arm thereon, and a yoke on said arm, having outwardly extending arms provided with straps, perforated lugs e^5 on said arms, and a frame f adapted to slide in said perforated lugs, substantially as and for the purposes set forth.

6. A luggage carrier for velocipedes, comprising therein a yoke or carrier frame, adapted to be attached to the frame of the velocipede, provided with outwardly extending arms, axles or pins in the forward ends of said arms, a finger piece connected with each axle or pin, and a ratchet wheel on the opposite end of each pin, pivoted pawls, comprising therein the curved portion k' and the sharp edges k^2 and k^3 , said pawls being capable of holding engagement with the teeth of said ratchet wheels, and spring j in engagement with said pawls, substantially as and for the purposes set forth.

ment with said pawls, substantially as and for the purposes set forth.

7. A luggage carrier for velocipedes, comprising therein a yoke or carrier frame, adapted to be attached to the frame of the velocipede, provided with outwardly extending arms, axles or pins in the forward ends of said arms, a finger piece connected with each axle or pin, and a ratchet wheel on the opposite end of each pin, pivoted pawls, comprising therein the curved portions k' and the sharp edges k^2 and k^3 , said pawls being capable of holding engagement with the teeth of said ratchet wheels, and springs j in engagement with said pawls, said springs being secured in perforated lugs e^8 and having coils j' loosely arranged on fingers e^9 on said yoke or carrier frame, substantially as and for the purposes set forth.

8. A luggage carrier for velocipedes, consisting of a clamp having a supporting arm thereon, and a yoke on said arm having holding straps, and a frame-portion connected with said yoke, said frame-portion being telescopically arranged in relation to said yoke, to enlarge or decrease the size of the luggage carrier, substantially as and for the purposes set forth.

In testimony that I claim the invention set forth above I have hereunto set my hand this 30th day of November, 1892.

SADIE M. BATES.
